UNITED STATES PATENT OFFICE.

OLIVER COLBORNE, OF CHICAGO, ILLINOIS.

PIE-CRUST-TRIMMING MACHINE.

No. 874,392.

Specification of Letters Patent.

Patented Dec. 24, 1907.

Application filed June 24, 1907. Serial No. 380,534.

To all whom it may concern:

Be it known that I, OLIVER COLBORNE, a citizen of the United States of America, and a resident of Chicago, county of Cook, and 5 State of Illinois, have invented certain new and useful Improvements in Pie-Crust-Trimming Machines, of which the following is a specification.

The main objects of this invention are to 10 provide an improved form of pie crust trimming machine, in which the trimming mechanism may be readily adjusted for handling different sizes of pies; to provide a machine of this class in which the crust trimming devices are normally at rest, being driven only 15 at times when actually performing the trimming operation; and to provide a device of this class in which the adjustment for different sizes of pies may be readily made with a 20 minimum replacement of parts. These objects are accomplished by the device shown in the accompanying drawings, in which

Figure 1 is a front elevation of a pie crust trimming machine constructed according to 25 this invention. Fig. 2 is a side elevation of the same. Fig. 3 is a section on the line 3—3 of one of the trimming roller arms, Fig. 2. Fig. 4 is a section on the line 4—4 of Fig. 2 showing the arrangement of the crust trimming rollers.

In the construction shown, the member 4 is carried at the upper end of a vertical shaft 5 and forms a horizontally disposed support for a pie tin. Said shaft is both rotatable 35 and longitudinally slidable in its bearing 6. A sleeve 7 is journaled concentrically of the shaft 5 in the same bearing, being supported by a collar 8 and carrying a bevel gear 9 at its lower end. The bevel gear 9 meshes with 40 a second gear 10 carried by the horizontal driving shaft 11, also journaled in the supporting frame 12.

The supporting frame has a part overhanging the support 4 and having splined therein a shaft 13. The shaft 13 is secured against rotation but is vertically slidable in its support and is normally urged to its lowest position by means of the spring 14, the downward movement being limited by a collar 15. The 45 shaft 13 carries a trimming member or head 16 at its lower end, said head being provided with a plurality of radially disposed adjustable arms 17 which carry fixed bearings 18. Each of the bearings has journaled therein a 50 spindle carrying at its lower end an idle crust trimming roller 19. These rollers are pref-

erably conical so that the parts of their peripheries which are adjacent to the pie tin support will be inclined inwardly and upwardly with respect to each other, as shown 60 in Figs. 1 and 2.

The arms 17 are preferably formed of two sections which interfit so as to slide longitudinally one upon the other. These parts are provided with registering slots and adapted 65 to be clamped in any position of adjustment by means of the bolts 20. The pie tin is indicated in position at 21 in Fig. 2. The rollers 19 are spaced equally distant from the axis of the shaft 5 so that, when said shaft is 70 lifted, the rim of the tin will bear equally upon each of the crust trimming rollers.

The vertical shifting of the shaft 5 is accomplished by means of the lever 22 which bears against the lower end of the shaft 5. 75 The lever 22 is normally depressed by a spring 23; and the weight of the shaft 5 and the support is sufficient to cause said support to move downward out of engagement with the trimming rollers 19 when the lever 80 22 is depressed. The lifting of the shaft 5 is accomplished by means of a cam 24 co-acting with the roller 25 at the opposite end of the lever 22. This cam should be of such shape 85 as to alternately hold the support in its upper and lower positions. The gears 9 and 10 should be so proportioned as to insure that the entire rim of the tin is traversed by said rollers while the support is raised. The interval during which the support is depressed 90 should be long enough to permit one tin to be removed and a second one to be brought in position below the trimming rollers.

The intermittent rotation of the support 4 is accomplished by means of the continuously 95 rotating bevel gears 9 and 10 and the clutch members 26 and 27. The clutch member 26 is rigid on the bevel gear 9 and the clutch member 27 is rigid on the shaft 5. The clutch member 27 is suitably located so 100 that when the shaft 5 is at the upper limit of its movement said clutch members will engage each other and rotate the support. In order to prevent rotation of the shaft 5 through friction with the sleeve 7 when said 105 shaft is in its lower position, the lower face of the clutch member 27 is provided with a plurality of stop notches which are engaged by the stop 28 on the supporting frame.

The operation of the device shown is as follows: The shaft 11 is continuously driven by the pulley 29 and the cam 24 causes the lever

22 to oscillate so as to alternately raise and lower the support 4. A pie tin with its contents is placed upon the support 4 and when said support is next raised, the rim of the tin 5 is carried into contact with the trimming rollers 19. The lifting of the shaft 5 carries the clutch member 27 out of engagement with the stop 28 and shifts it into engagement with its mate 26. This causes the support 10 to rotate. The movement of the shaft 5 is sufficient to raise the trimming member 16 slightly and insure a uniform pressure between the rollers 19 and the rim of the tin.

What I claim as my invention and desire 15 to secure by Letters Patent is

1. In a crust trimming machine, the combination of a pair of members mounted in axial alinement and movable axially toward and away from each other, one of said members being adapted to support a pie tin and the other being adapted to engage the edge of such tin for trimming a pie crust thereon, means for rotating one of said members relatively to the other and controlling means 20 adapted to automatically start and stop such relative rotation when said members are moved toward or away from each other.

2. In a pie machine, the combination of a pair of members movable toward and away 30 from each other, one of said members being adapted to support a pie tin, a trimming roller on the other of said members adapted to engage the edge of such tin for trimming a pie crust thereon, mechanism adapted to 35 rotate one of said members relatively to the other, and means controlled by the relative movement of said members toward and away from each other for starting and stopping the operation of said mechanism.

40 3. In a pie machine, the combination of a pair of members movable toward and away from each other, one of said members being adapted to support a pie tin, a plurality of trimming rollers on the other of said members, arranged symmetrically about the axis of such tin and adapted to engage the edge of such tin for trimming a pie crust thereon, mechanism adapted to rotate one of said members relatively to the other, and means 45 controlled by the relative movement of said members toward and away from each other for starting and stopping the operation of said mechanism.

45 4. In a crust trimming machine, the combination of a pair of members movable toward and away from each other, one of said members being adapted to support a pie tin and the other being adapted to engage the edge of such tin for trimming the crust there- 55 on through the relative rotation of said members, mechanism for rotating one of said members relatively to the other when they are brought together, and means for preventing such relative rotation when said members 60 are separated.

5. The combination of a support for a pie tin, trimming mechanism adapted to engage the edge of a tin on said support, said support and trimming mechanism being relatively movable toward and away from each other, means for rotating said support relatively to the trimming mechanism, and a clutch controlling the operation of said means and adapted to be automatically closed and opened during the relative movement of said support and trimming mechanism respectively toward and away from each other.

6. A crust trimming machine comprising a horizontally disposed support for a pie tin, a member mounted above said support, a plurality of crust trimming rollers journaled on said member, being equally spaced with respect to the axis of said support and having the adjacent parts of their peripheries inclined toward said axis, mechanism for lifting said support to carry the tin into contact with said trimming rollers and simultaneously rotating said tin.

7. In a pie crust trimming machine, the combination of a support for a pie tin mounted to rotate on a vertical axis, a plurality of trimming rollers journaled on fixed axes above said support and equally spaced with respect to the axis of said support and mechanism for raising said support to carry the tin into contact with said rollers and adapted to simultaneously rotate said tin.

8. In a pie crust trimming machine, the combination of a support for a pie tin, a plurality of conical trimming rollers journaled above said support on axes spaced equally with respect to the axis of said support, mechanism for lifting said support to carry the tin into engagement with said rollers and adapted to simultaneously rotate the tin, said rollers being idle and free to rotate independently of each other.

9. The combination of a support for a pie tin, a plurality of idle rollers journaled on fixed axes above said support and equally spaced with respect to the axis of said support, said rollers having the adjacent parts of their peripheries inclined to the axis of said support, means for shifting said support vertically to carry the tin into contact with said trimming rollers, and mechanism for rotating said support when in its lifted position, said support being adapted to remain normally stationary when in its normal position below and out of engagement with said rollers.

10. In a pie crust trimming machine, the combination of a horizontally disposed support for a pie tin, a frame overhanging said support, a plurality of idle trimming rollers mounted on said frame and equally spaced with respect to the axis of said support, said support being movable vertically to carry the tin into and out of engagement with said

rollers, and the axes of said rollers being adjustable toward and away from the axis of said support to suit different sizes of tins.

11. The combination of a vertically disposed shaft, a support for a pie tin mounted thereon, a frame overhanging said support, a plurality of idle trimming rollers mounted to rotate on fixed axes in said frame and arranged symmetrically around said shaft, 5 said shaft being longitudinally movable to carry the tin into engagement with said trimming rollers, a member journaled concentrically of said shaft and adapted to be continuously driven, and a pair of clutch members secured respectively to said member and shaft and adapted to engage with each other for rotating said shaft when the pie tin is in engagement with said trimming rollers.

20 12. In a pie crust trimming machine, the combination of a vertically disposed shaft, a support for a pie tin mounted thereon, said shaft being mounted to rotate on its own axis and to slide vertically in its bearing, a 25 frame overhanging said support, a plurality of trimming rollers mounted to rotate on fixed axes on said frame and arranged symmetrically around said shaft, a clutch member journaled concentrically of said shaft and 30 adapted to be continuously driven, means for shifting said shaft vertically to carry the tin into engagement with said trimming rollers, and a second clutch member on said shaft located so as to mesh with said first clutch 35 member and cause the rotation of said support when said support is shifted vertically into engagement with said trimming rollers.

13. In a pie crust trimming machine, the 40 combination of a vertically disposed shaft, a support for a pie tin mounted thereon, said shaft being mounted to rotate on its own axis and to slide vertically in its bearing, a frame overhanging said support, a plurality of trimming rollers mounted to rotate on 45 fixed axes on said frame and arranged symmetrically around said shaft, a clutch member journaled concentrically of said shaft and adapted to be continuously driven, means for shifting said shaft vertically to carry the 50 tin into engagement with said trimming rollers, a second clutch member on said shaft located so as to mesh with said first clutch

member and cause the rotation of said support when said support is shifted vertically into engagement with said trimming rollers, 55 and mechanism for intermittently raising and lowering said shaft.

14. A crust trimming device comprising a horizontally disposed support for a pie tin, a member mounted above said support, being 60 secured against rotation and adapted to yield vertically, said member being normally urged downward, a stop limiting the downward movement of said member, a plurality of crust trimming rollers journaled on said 65 member on axes equally spaced with respect to the axis of said support, the parts of the peripheries of said rollers which are adjacent to said shaft being inclined so as to converge upwardly toward each other, and mechanism adapted to lift said support to carry the 70 tin into contact with said trimming rollers and cause the tin to rotate while in such contact.

15. In a pie crust trimming device, the 75 combination of a support for a pie tin, trimming mechanism adapted to engage the rim of a tin on said support for trimming off the surplus dough, said support and trimming mechanism being relatively movable toward 80 and away from each other axially of the tin, and mechanism for imparting relative rotation to said support and trimming mechanism to cause said trimming mechanism to travel about the rim of the tin, said mechanism being intermittently operated and being controlled in its operation through such relative axial movement of the support and trimming mechanism. 85

16. The combination of a support for a pie 90 tin, a plurality of trimming rollers journaled above said support on axes disposed transverse to the plane of the pie tin and arranged symmetrically with respect to the axis of the tin, and said trimming rollers being adjustable toward and away from the axis of the tin 95 to suit different sizes of tins.

Signed at Chicago this 20th day of June 1907.
